[57] ABSTRACT

There is provided a ganged variable resistor comprising a cover having at least a bottom wall and a pair of side walls, a bearing mounted on the bottom wall of the cover, an actuating shaft rotatably supported by the bearing to extend therethrough, a plurality of bent portions formed on the sides of each of the cover side walls and arranged with some spacing therebetween to securely hold in place the insulating bases of a plurality of variable resistors at the respective stages, and a plurality of brushes mounted on the extension of the actuating shaft in such a manner that each of the brushes is slidable on the resistance element mounted on each of the insulating bases. The ganged variable resistor of this invention is advantageous in that the number of component parts is reduced to ensure simplified assembling operation and significant reduction in the thickness of the assembly.

FIG. 5

GANGED VARIABLE RESISTOR

The present invention relates to an improved ganged variable resistor wherein the number of the component parts is reduced and the assembling operation is simplified to ensure a simplified assembly and significant reduction in the thickness of the assembly.

The invention will be described in greater detail with reference to the accompanying drawings, in which:

FIG. 1 is a sectional view of a prior art ganged variable resistor;

FIG. 2 is a sectional view of a ganged variable resistor according to an embodiment of the invention;

FIG. 3 is a perspective view showing the cover of the ganged variable resistor of FIG. 2 before the assembling thereof; and

FIG. 4 is a perspective view showing the extension shaft and the brush used in the ganged variable resistor of FIG. 2.

FIG. 5 is a view of a base of the ganged variable resistor of FIG. 2.

In a known type of ganged variable resistor, as for example illustrated in FIG. 1, the spacing between the respective variable resistors is provided in such a manner that a cup-shaped metallic cover 2 of the preceding variable resistor is secured, as by calking, to an insulating base 1 of the following variable resistor, and then the fitting legs (not shown) provided on the open end side of the preceding metallic cover 2 is secured, as by calking, to an insulating base 1' of the preceding variable resistor (this may be the insulating base 1 of the said following variable resistor).

With the construction described above, it is necessary to use as many metallic covers 2 as there are variable resistors, and therefore it is difficult to reduce the number of processing steps in the assembling operation. Another disadvantage of this prior art assembly is that an undesirably large spacing is required for the metallic cover 2 of the preceding variable resistor so that the fitting legs on a metallic cover 2' of the following variable resistor (this may be the metallic cover 2 of the preceding variable resistor) may be bent and secured in place by calking, and this is detrimental to the desired reduction in the thickness of the assembly.

In FIG. 1, numeral 3 designates an actuating shaft rotatably supported by a bearing 4 to extend therethrough, 5 an extension shaft securely connected to the actuating shaft 3, 6 resistance elements mounted on the respective insulating bases 1 (1'), 7 brush holders mounted on the actuating shaft 3 and the extension shaft 5, 7' a brush holder formed integral with the extension shaft 5 with brushes 8 fixedly mounted on the brush holders 7 and the brush holder 7' in such a manner that each of the brushes 8 slides over the resistance element 6 in accordance with the rotation of the actuating shaft 3. Numeral 9 designates contacts normally in contact with the portion of the respective brushes 8, 10 internal terminals to which the contacts 9 are secured by calking, 11 intermediate bearings for securing, as by calking, the metallic covers 2 (2') to the respective insulating bases 1 (1'). The external terminals (not shown) are brought out from the ends of the respective resistance elements 6.

It is therefore an object of the present invention to overcome the foregoing difficulty.

In accordance with the present invention, there is thus provided a new and improved ganged variable re-

sistor wherein the respective insulating bases are held in place by a single common cover and the use of brush supporting members heretofore used for fixedly mounting brushes is eliminated to reduce the thickness of the assembly and decrease the number of assembling operations.

Referring now to FIGS. 2 through 4, an embodiment of the present invention will be described.

In FIGS. 2 through 4, numeral 12 designates a metallic cover having an open end and an open side, and a bearing 14 is secured, as by calking, to a bottom wall 12a of the metallic cover 12 through a shield plate 13. A metallic actuating shaft 15 is rotatably supported by the bearing 14 to extend therethrough. Numeral 16 designates an extension shaft of plastic material which is not circular and which is securely connected to an upper end 17 of the actuating shaft 15 projecting into the cover 12, and the extension shaft 16 is adapted to rotate along with the rotation of the actuating shaft 15. A brush holder 18 is formed integral with the extension shaft 16 at its lower end adjoining the upper end 17 of the actuating shaft 15. The extension shaft 16 and the actuating shaft 15 may be made of plastic material as a single unit. Numeral 19 designates a brush fixedly carried on the brush holder 18, and one end of the brush 19 is in contact with a horseshoe resistance element 21 mounted on the lower surface of a rectangular insulating base 20 so that the end of the brush 19 slides over the resistance element 21 as the brush holder 18 is rotated along with the rotation of the actuating shaft 15. A rotation stop extension 22 is formed as an integral part of the brush holder 18 and this stop extension 22 engages a rotation stop projection 23 formed by cutting and raising a portion of a side wall 12b facing the open side of the metallic cover 12 to limit the angle of rotation of the actuating shaft 15. Numeral 24 designates a contact secured to the lower surface of the insulating base 20 by calking an internal terminal 25 and the contact 24 is normally in electric contact with the resistance element 21. In this embodiment, the insulating base 20 is placed on inwardly protruding insulating base supports 26 formed by cutting and raising portions of side walls 12c and 12d adjoining the open side of the metallic cover 12, and the upward movement of the insulating base is prevented by lower side tapered portions 27a of bent portions 27 provided on the sides of the side walls 12c and 12d. In other words, the insulating base 20 is securely held between the insulating base supports 26 and the bent portions 27. The insulating base 20 is provided with a central opening 28 through which the extension shaft 16 extends. Numeral 29 designates a brush holder of metallic or plastic material which is dish-shaped in section and which is mounted on the extension shaft 16 to be positioned on the insulating base 20. Numeral 30 designates a brush mounted on the extension shaft 16 by means of a fitting opening 30a so that it is placed on the brush support 29, and the brush 30 is prevented from shifting in the direction of rotation of the extension shaft 16 by means of locking pawls 30b formed on the inner periphery of the fitting opening 30a to fit in grooves 16a formed on the outer surface of the extension shaft 16. Numeral 31 designates an insulating base mounted on upper side flat portions 27b of the bent portions 27 formed in the side walls 12c and 12d of the metallic cover 12, 32 a horseshoe resistance element in contact with one end of the brush 30, 33 a contact simi-

lar in function with the contact 24, 34 an internal terminal similar in function with the internal terminal 25. Similarly with the insulating base 20, the upward movement of the insulating base 31 is prevented by lower side tapered portions 35a of bent portions 35 formed on the sides of the side walls 12c and 12d of the metallic cover 12 and spaced away from the bent portions 27 by some distance. Numeral 36 designates an insulating base securely held between upper side flat portions 35b of the bent portions 35 and lower side tapered portions 37a of bent portions 37, 38 an insulating base held securely between upper side flat portions 37b of the bent portions 37 and lower side tapered portions 39a of bent portions 39. In the like manner as the insulating base 20, the insulating bases 31, 36 and 38 are respectively provided with central openings 40, 41 and 42 through which the extension shaft 16 extends. Numerals 43 and 44 designate brush holders similar in function with the brush holder 29. Numerals 45 and 46 designate brushes, 47 and 48 horseshoe resistance elements, 49 and 50 contacts, 51 and 52 internal terminals all of which function in the above-described manner. Numeral 53 designates a metallic cover mounted on the open end of the metallic cover 12.

In this embodiment, the external terminals (not shown) are brought out from the ends of the respective horseshoe resistance elements 21, 32, 47 and 48. Further, the side walls 12c and 12d of the metallic cover 12 are respectively provided with an inwardly protruding positioning projection 54 extending in the same direction as the extension shaft 16, and the positioning notches 60 formed on the edges of the insulating bases 20, 31, 36 and 38 are fitted on the positioning projections 54 to prevent the movement of the insulating bases 20, 31, 36 and 38 in the horizontal direction.

The ganged variable resistor described above is assembled in the following manner. Firstly, the metallic cover 12 and the bearing 14 are brought together after which the actuating shaft 15 is rotatably fit in the bearing 14 through lubricating oil and the extension shaft 16 is securely connected to the upper end 17 of the actuating shaft 15. In this condition, the bent portions 27, 35, 37 and 39 formed on the side walls 12c and 12d of the metallic cover 12 have not been bent as yet. After the insulating base 20 equipped with the resistant element 21, the contact 24 and so on has been placed on the insulating base supports 26 formed in the side walls 12c and 12d, the bent portions 27 are bent to securely hold the insulating base 20 in place. In this case, the positioning notches formed on the edges of the insulating base 20 are fitted on the positioning projections 54 to place the insulating base 20 on the insulating base supports 26. Thereafter, the brush holder 29 is mounted on the extension shaft 16 so that it is positioned on the insulating base 20, and then the locking pawls 30b are fitted in the grooves 16a to mount the brush 30 on the extension shaft 16. Thereafter, the insulating base 31 is placed on the upper side flat portions 27b of the bent portions 27, and then the bent portions 35 are bent to securely hold the insulating base 31 in place. Then, the similar operations as described in connection with the insulating base 20 are carried out. The similar process is repeated with the insulating bases 36 and 38, and finally the upper cover 53 is mounted in place.

While, in the embodiment of this invention described above, the brushes 33, 45 and 46 are respectively mounted through the brush holders 29, 43 and 44 on

those portions of the extension shaft 16 above the insulating bases 20, 31 and 36, the brushes 33, 45 and 46 may be respectively directly carried on the insulating bases 20, 31 and 36. Further, it is possible to use plastic covers of sufficient strength in place of metallic covers. Further, it is sufficient if the metallic cover 12 comprises at least the bottom wall 12a and a pair of opposed side walls 12c and 12d, and the side wall 12b may be eliminated if a rotation stopping mechanism is separately provided. Furthermore, while, in the embodiment described above, the insulating base 20 is placed on the insulating base supports 26, it may be placed on the similar bent portions as the bent portions 27, 35, 37 and 39.

What we claim is:

1. An improved ganged variable resistor assembly including a plurality of variable resistors, wherein the improvement comprises a cover member having at least a bottom wall and a pair of side walls, an actuating shaft supported by and extending through a bearing provided on said bottom wall, said actuating shaft including an extension, a plurality of bent portions formed on the sides of each of said side walls and arranged at predetermined intervals to securely hold the insulating bases of said plurality of variable resistors in place, and a plurality of brushes mounted on said extension of said actuating shaft whereby each of said brushes is slidable on the associated one of resistance elements provided on said insulating bases.

2. A ganged variable resistor assembly according to claim 1, wherein said bent portions on said cover member are arranged and bent inwardly so that each of said insulating bases is positioned by an upper side flat portion of said bent portions and is secured by a lower side tapered portion of a proceeding bent portion associated with each of said insulating bases.

3. A ganged variable resistor assembly according to claim 1, wherein said brushes each slidable on the resistance element mounted on each of said insulating bases are directly mounted on an extension shaft of a plastic material which is placed on said extension of said actuating shaft and whose section is not circular, and each of said brushes is supported by the associated one of said insulating bases.

4. A ganged variable resistor assembly according to claim 1, wherein each of said pair of side walls of said cover member is provided with an inwardly protruding positioning projection extending along said pair of side walls in the same direction with said extension of said actuating shaft, and each of said insulating bases is provided with positioning notches formed on the both edges of each of said bases to receive said positioning projections.

5. A ganged variable resistor assembly according to claim 3, wherein said cover member further includes a side wall provided with a rotation stop projection in addition to said pair of side walls, said extension shaft is provided with a brush holder at that portion thereof adjoining said bottom wall of said cover member, and said brush holder is formed as an integral part thereof with a rotation stop extension to engage with said rotation stop projection to limit the angle of rotation of said actuating shaft.

6. A ganged variable resistor assembly according to claim 3, wherein each of said brushes is supported by the associated one of said insulating bases through brush holding means.
